UNITED STATES PATENT OFFICE.

FRANK X. PFLUGER, OF PORTLAND, OREGON.

WOODEN TUB.

Application filed November 3, 1921. Serial No. 512,501.

To all whom it may concern:

Be it known that I, FRANK X. PFLUGER, a citizen of the United States, and a resident of Portland, county of Multnomah, and 5 State of Oregon, have invented a certain new and useful Improvement in Wooden Tubs, of which the following is a specification.

My invention has for its purpose the improvement of the construction of wooden ice cream tubs, and relates particularly to the bottom of these tubs.

These tubs are usually constructed of cedar wood, and since they receive a great deal of handling, in being shipped to and fro, the knocks to which the bottom is subjected has a tendency to render it loose and leaky; which, of course, wastes the brine, and may uncover the cream container to such extent as to spoil the ice cream.

Furthermore, the knocks which the bottom of the staves of these tubs receive tend to crush the bottom ends of the staves. It has been customary to affix a false piece of 25 harder wood on the under side of the bottom of the tub; but this did not provide a complete remedy, because cedar wood does not hold nails well, and so the false piece became loose and no longer functioned properly.

Besides the false piece did not function to prevent the bottom of the tub from becoming loose and leaky, which condition might arise because of the bottom of the tub drying out and shrinking.

The object of my invention is to provide a bottom for these wooden tubs which will make the bottom of the tub as a whole so solid that it will remain in good condition 40 indefinitely.

I attain my object in a wooden tub comprising staves and a one piece bottom, the latter having a flange at the top, which flange projects in a horizontal plane and is of wedge shape in cross section; the bottom further having second flange parallel with and below the first mentioned flange; and preferably a third flange arranged like the second flange; said second and third flanges 45 being of triangular cross section with the vertex of the triangle projection beyond the periphery of the bottom; the staves being provided on their interior faces with a groove adapted to receive said wedge like top flange of the bottom piece. Thus, on the assembly and pressing of the staves of

the tub about the bottom piece, the top flange of the latter will wedge in said groove in the staves, and said second and third flanges will be pressed into the sides 60 of the staves, and form with the latter auxiliary liquid tight joints; at the same time contributing towards the rigidity of the bottom of the tub as a whole.

My invention is illustrated in the accompanying drawings, in which:

Fig. 1 is a side elevation of my improved tub with a portion broken away so as to show the above mentioned details of the bottom of the tub;

Fig. 2 is a top view of my tub;

Fig. 3 is a sectional detail illustrating the construction of the bottom view which is shown in exterior view and the effect produced when the staves are pressed about the 70 bottom piece; and

Fig. 4 is a sectional detail illustrating the above mentioned detail of construction, the bottom piece being shown in section and as removed from the staves and the face of the staves have indicated therein the liquid tight seats which will be formed on its interior faces with said flanges of the bottom piece when the staves are pressed about the latter.

It is to be noted in these drawings that the only seat prepared for my improved one piece bottom is a notch cut near the bottom of the tub. This notch *g* is slightly smaller in width than the uppermost flange *d* of the tub bottom *b*. When the sides of the tub *a* are compressed by means of the iron bands *c*, *c'* and *c''* this projecting wedge *d* is forced into the notch *g* and the action of the wedge like sides forces it wider and make a water tight joint. Besides this action of the uppermost flange *d* the two triangular flanges *e* and *f* are formed in the tub bottom and are pressed into the stave sides of the container and thus make their own seat. This not only forms an added water tight seal but also makes the bucket 90 more rigid and the natural racking is therefore much better taken care of. These triangular wedge flanges have no seats prepared for them but the only seats which they have are the indentations that they make upon the action of compression of the iron bands as before noted. As my improved tub bottom is made of only one piece of material and as it will seat in the staves at three separate places, all of which

100 are a tight fit, it can be noted that big ad- 105
110

vantages are attained. The depression between the two triangular flanges in this tub bottom *b* provides a space between the bottom *b* and the side walls *a* which can collect any seepage that might escape past the flanges *d* and *e*. This provides a reservoir in which the seepage water may be collected which would tend to swell this joint and therefore maintain the pressure between the bottom and the side walls. Without this 10 drying out of the bottom *b* and the side walls would tend to relieve the pressure and thus cause the flanges in my one piece bottom to become removed 15 from their seats and thus permit leakage by the tub bottom until the water had swelled these parts again and restored this pressure.

In the drawings the staves are connected 20 to each other in conventional manner by means of the hoops *c*, *c'* and *c''* and at the top by means of wedges which tend to keep them from spreading apart because they are placed on the joints between the staves.

25 It will be noted that the third flange is located near the base or bottom face of the tub and thus particularly functions to stiffen and support the bottom ends of the staves and prevent their being crushed in by the 30 knocks which the tub receives.

I preferably make my tub with a slight flare as shown in Fig. 1 and the staves are pressed about the bottom piece by means of the usual iron bands.

35 I claim:

1. A wooden tub comprising staves and a one-piece bottom, the latter being provided

with a peripherally projecting flange of wedge form in cross section, and being provided further with a second flange located 40 below said first mentioned flange, and with a third flange located adjacent the under side of the bottom piece, said second flange being of triangular cross-section, the staves being provided on their interior faces with a groove to receive said wedge like top flange of the bottom piece, whereby, on the assembly and pressing of the staves about its bottom piece said flange of triangular cross-section will be pressed into the 50 opposed faces of the staves and form therewith a liquid tight joint, such joint also contributing to the rigidity of the bottom of the tub as a whole.

2. A wooden tub comprising staves and a one-piece bottom, the latter being provided with a peripherally projecting flange of wedge form in cross-section, and being provided further with a second flange located 55 below said first mentioned flange, and with a third flange located adjacent the under side of the bottom piece, said second and third flanges being of triangular cross-section, the staves being provided on their interior faces with a groove to receive said 60 wedge like top flanges of the bottom piece, whereby, on the assembly and pressing of the staves about its bottom piece said flanges of triangular cross section will be pressed into the opposed faces of the staves and 65 form therewith a liquid tight joint, such joint also contributing to the rigidity of the bottom of the tub as a whole.

FRANK X. PFLUGER.
